SELENIUM RECTIFIER

Edward Arthur Richards and Leslie James Ellison, London, England, assignors to International Standard Electric Corporation, New York, N. Y.

Application February 23, 1940, Serial No. 320,380
In Great Britain March 17, 1939

7 Claims. (Cl. 175—366)

This invention relates to metal rectifiers, which usually comprise a number of rectifier elements arranged in series. One theory of the action of a metal rectifier element is that it consists of an imperfect conductor and a good conductor separated by a barrier layer of extreme thinness. In the case of the selenium rectifier the selenium forms the imperfect conductor and a sprayed metal layer the good conductor and the barrier layer is formed at the surface between the selenium and the sprayed layer. In this specification we call the layer of selenium or the like the active electrode and the other electrode we call the counter electrode. Each rectifier element therefore comprises an active electrode and a counter electrode, and the invention is concerned with rectifiers of the kind in which the elements are electrically susceptible to pressure such that when pressure is exerted thereon there is a tendency for an increase to take place in the reverse current of the rectifier; such is the case in selenium rectifiers. Selenium rectifiers as at present manufactured may have a metallic contact washer, for example spring brass, to make connection to a metal surface forming the counter electrode. By way of explanation it may be mentioned that this method of making connection has certain disadvantages at present, particularly when the rectifier has to be protected against moisture, because if the required protection is provided by treating the complete rectifier with varnish, for example by dipping, it is found that the varnish shows a tendency to penetrate between the contact washer and the metal surface of the counter electrode, which may for example be provided by spraying. This penetration of the varnish introduces a high resistance at the point of contact, and leads to breakdown of the rectifier. We have found that it is not possible to dispense with the contact washer, and to clamp the elements tightly together as in a copper oxide rectifier, in view of the fact that any considerable increase of pressure causes an increase in the reverse current of the rectifier. Apart from this difficulty, which is, however, decisive, it would be possible to make the connection to the counter electrode by means of a plain metal washer at the centre of the disc and to clamp the whole rectifier tightly so that varnish could not penetrate between the actual connection points. We believe that the increase in reverse current which takes place when the pressure is applied is due to pressure acting on the barrier layer between the active electrode and the counter electrode. An object of the invention is to overcome the above difficulty.

According to the invention there is provided a metal rectifier of the kind referred to comprising an assembly of rectifier elements wherein pressure is applied to each of the elements only at a part thereof at which the counter electrode is not in contact with the active electrode.

In more detail the invention includes a metal rectifier comprising an assembly of rectifier elements wherein the active electrode of each element is in part insulated from the counter electrode thereof in such a manner that when the elements are pressed together the pressure on the counter electrode of an element is limited to that portion which is insulated from the active electrode thereof. In this manner the pressure will not cause any increase or at all events any appreciable increase in the reverse current of the rectifier. The required insulation may be effected either by the use of an insulating washer of mica, material known under the registered trade-mark Bakelite, or other suitable insulating material, or by coating the active electrode, e. g., the selenium, with a suitable varnish or enamel or with a material such as polystyrene.

Dealing particularly with the manufacture of rectifiers in which the elements may be assembled on a central insulating spindle an area in the centre of each electrode may be insulated, after which the whole surface area of the insulated face may be sprayed with metal so that the sprayed metal covers both the active electrode and the insulated surface thereof, after which the elements may be assembled on the spindle in the usual manner, metal spacing washers being provided to make contact with the sprayed metal surface at the centre of each element in order to connect the elements in series or to provide a connection to the external circuit.

In order that the invention may be clearly understood and readily carried into effect, reference is directed to the accompanying drawing which shows diagrammatically and by way of example embodiments of the invention.

in this drawing:

Figs. 1 and 1A are respectively a sectional elevation and a front view of an element embodying the invention mounted upon an insulating spindle;

Figs. 2 and 4 are views similar to Fig. 1 of modified constructions; and

Fig. 3 is a longitudinal sectional view of a rectifier assembly embodying the invention.

Referring particularly to Fig. 1, the reference 1 indicates a disc of iron or other suitable metal

having the whole surface of one face thereof coated with selenium at 2. After the selenium has been treated, in known manner, to develop its rectifying properties, a circular area is covered with an insulating washer or insulating varnish as at 3 and then the whole surface including the exposed surface of the selenium and the insulating material at 3 is sprayed with metal 4 which forms the counter electrode where it is in contact with the selenium. The portion of the metal 4 which covers the insulating material at 3 serves merely to conduct the current from the centre to the working portion of the rectifier. The element described above is then provided with a metal, e. g., a brass washer 5, which may be pressed tightly against the counter electrode metal 4 in view of the fact that the pressure is applied to a part of the metal which is insulated from the selenium 2. As shown, the element may be mounted upon a spindle 6 extending through a central aperture provided for the purpose.

The present invention may be applied with advantage to many sizes and shapes of rectifiers, but is of special importance in connection with small rectifiers in which the elements may be assembled in an insulating tube. In such an assembly we have found that if sufficient spring pressure is applied at the end of the tube to maintain satisfactory contact, the reverse current attains too high a value, while if the spring pressure is reduced to the correct value when considering the reverse current, the pressure will not be sufficient to make satisfactory electrical contact.

In Fig. 2 an iron or like base part 1 is coated with selenium 2 and then covered with insulating material 3 leaving a small space 7 central of the selenium uncovered, the area of the space 7 determining the active surface of the rectifier element. The insulating material, if in the form of a separate disc, is cemented to the selenium surface and the outer surface of the insulating material and the central exposed portion of the selenium is then sprayed in the normal way with contact metal 4 to form the counter electrode. The result of this construction is that only the portion of the selenium exposed through the holes is actually effective, and that pressure applied to the metal 4 of the counter electrode is not transmitted direct to the selenium but is transmitted to the insulating material 3. These elements can therefore be built up in series and any required pressure can be put upon the assembly without substantial ill effects. Fig. 3 shows an assembly of elements disposed within an insulating tube 8 closed at each end by insulating plates 9 through which connection may be made to the rectifier elements by means of connectors 10. The elements are arranged in series as shown each element comprising an iron or like disc 1, a selenium coating 2, an insulating coating 3, leaving a central space 7 and a disc 4 forming the counter electrode. At the negative end of the assembly the connector 10 terminates in an abutment 11 against which the disc 1 of the end element is tightly pressed and at the positive end the connector 10 is secured to a steel or like spring 12 which presses tightly against the disc 4 of the end element. It is also possible in accordance with the invention to remove the selenium from a portion of the base or to apply the selenium selectively to the base in such a manner that a portion of the base remains uncoated and then to apply pressure in such a manner that the pressure on the

counter electrode is limited to that part of the counter electrode which corresponds to the uncoated part of the base; in this manner it will be understood that no substantial pressure is exerted upon the barrier layer between the active electrode and the counter electrode. A construction according to this embodiment of the invention is shown in Fig. 4 in which 1 indicates the base metal, and 2 a layer of selenium which covers a part of the base 1. The part of the base 2 which is not coated with selenium is covered with an insulating material at 7 or provided with an insulating washer in order to prevent short circuits and the surface of the selenium and the insulating material are then provided with a metallic coating 4 to form the counter electrode and a washer 5 is positioned as shown to press the parts of the element together and to make contact with the counter electrode. 4. In this manner pressure may be applied to the element through the washer 5 which is of substantially the same size as the uncoated part of the base with the result that the pressure is transmitted through the washer 5, the counter electrode 4, the insulation 7 and the base 1 and not through a part of the element at which the active electrode is in contact with the counter electrode. It may be mentioned that the insulation 7 may be varnish, polystyrene or any other suitable insulating material.

What is claimed is:

1. A metal rectifier element comprising a metal base plate, a layer of active material coated on substantially all of one surface of said base plate, a layer of insulating material on said active material layer, said insulating layer being substantially coextensive with said active material layer and having a generally centrally located aperture whereby a portion of said active material is exposed, and a counter electrode plate substantially coextensive with said insulating layer, said counter electrode being conductively associated with the exposed portion of said active layer through said aperture.

2. A metal rectifier element comprising a metal base plate, a layer of active material coated on substantially all of one surface of said base plate, a layer of insulating material on said active material layer, said insulating layer being substantially coextensive with said active material layer and having a generally centrally located aperture whereby a portion of said active material is exposed, and a counter electrode plate substantially coextensive with said insulating layer and formed with a generally centrally located protruding portion extending through said aperture an amount substantially equal to the thickness of said insulating layer.

3. A metal rectifier element according to claim 1, wherein said insulating layer comprises a coating of varnish.

4. A metal rectifier element according to claim 1, in which said counter electrode is in part insulated from said active material by a marginal coating applied to said active electrode, whereby the central part thereof is exposed.

5. A metal rectifier comprising an assembly of rectifier elements of the character defined by claim 1 disposed end to end upon an insulating spindle and housed within an insulating casing, and means for resiliently engaging said elements with each other, whereby when pressure is applied to the elements the pressure is taken by that part of the counter electrode of each ele-

ment which is insulated from the active electrode.

6. A metal rectifier element comprising a base electrode, an active electrode thereon, said active electrode being substantially coextensive with said base electrode, a counter electrode in contact with said active electrode, and means for insulating a portion of said counter electrode

from a corresponding and adjacent portion of said active electrode.

7. A metal rectifier element according to claim 1 wherein the insulating layer comprises a coating of polystyrene.
